UNITED STATES PATENT OFFICE.

JERRE T. RICHARDS, OF CHICAGO, ILLINOIS.

AUTOMATIC COALING-BUCKET.

1,062,359.

Specification of Letters Patent.

Patented May 20, 1913.

Application filed March 22, 1911. Serial No. 616,194.

To all whom it may concern:

Be it known that I, JERRE T. RICHARDS, a citizen of the United States, residing at Chicago, in the county of Cook and State 5 of Illinois, have invented certain new and useful Improvements in Automatic Coaling-Buckets, of which the following is a specification.

This invention relates to an improved construction of automatic coaling buckets for receiving, carrying and discharging coal from an adjacent storage bin to a locomotive tender, or other receptacle, in measured quantities.

15 This invention has for its object to provide a comparatively simple, efficient, and durable device which, as shown, is normally positioned adjacent the discharging end of a coal chute having an end gate adapted 20 to be actuated from closed to opened position, and vice versa, by the movement and action of the coal bucket adjacent thereto.

Another object is to provide an efficient 25 end gate construction in combination with the movable coaling bucket; and a further object is to provide a practical construction for regulating the position, movement, and travel of the coaling bucket.

The invention further consists in the features of construction and combination of parts hereinafter described and claimed.

In the drawings Figure 1 is a side elevation of the automatic coaling bucket in normal position adjacent the coal chute, and 35 indicating in dotted lines the further extreme position of the bucket in dumping or discharging position; and Fig. 2 is an enlarged side elevation more particularly of the coaling bucket and end chute gate, the 40 dotted lines indicating a somewhat advanced position of the coaling bucket and gate with which it coöperates for advancing it to closed position preparatory to dumping and discharging the fuel.

45 As indicated, the coaling bucket 3 comprises an inner enlarged body portion 4 and an outer contracted discharge orifice 5, which is tiltably mounted as at 6 upon opposite bucket carriers 7 pivotally secured at 50 their lower ends 8 to a supporting post or column 9. Upon the outer side bucket walls are formed stop lugs, the upper lug 10 serving to retain the coaling bucket 3 in normal position adjacent the mouth of a coal chute 11, and the lower stop lug 12 serving to regulate the downward pitch of the coaling

bucket 3 when in the extreme advanced position indicated by dotted lines in Fig. 1, the respective lugs 10 and 12 contacting and engaging the bucket carrying arms 7. As 60 shown, a chain or cable 13 is secured at one end to an eye-bolt 14 in the post or column 9 and its other end is secured to a retainer 15 attached to the bottom wall or face of the coaling bucket 3 for tilting the bucket 65 downwardly when brought into the advanced position indicated.

An end chute gate 16 comprising a gate portion 17, having side arms 18 is pivotally secured, as shown, in the side walls of the 70 chute 11, said side arms having upper bent portions 19 to the ends of which are attached cables or ropes 20 traveling on pulleys 21, and carrying at their lower ends weights 22 for causing the end chute gate 75 16 to normally assume a closed position at the discharge mouth of the coal chute 11, as indicated by dotted lines.

The opposite bucket carriers 7 have attached thereto cables or ropes 23 traveling 80 upon pulleys 24 secured to the column or post 9 adjacent thereto, and the lower ends 25 of the ropes or cables 23 are likewise weighted for causing the coaling bucket 3 when empty to be carried back to normal 85 position adjacent the coal chute 11. Pivotally secured upon the post or column 9 of the coal structure is shown an upright bar 26 to which is pivotally attached one end of an intermediate controlling lever 27, 90 and at the upper end of the bar 26 is pivotally secured one end of a gate actuating lever 28 having its other end pivotally attached to the side gate arm 18. A connecting member 29 has its upper end mounted 95 in the wall of the coal chute 11, as shown, and its lower end is pivotally attached to one end of the lever 27 adjacent which are downwardly projecting retainers 30 and 31. The retainer 30 may be of smaller proportion than the retainer 31, and, between said 100 retainers, the rear upper end bucket wall 32 is adapted to be positioned and engaged, and when the bucket is moved forward toward discharging position the shorter retainer 30 is proportioned to permit the rear bucket wall 32 to clear the same as indicated in Fig. 2. It will thus be seen that this construction permits the coal bucket to be locked in normal position adjacent the coal 110 chute for leading the same, and that the action of the end chute gate 16 corresponds

with the movement of the intermediate lever 27 since both the levers 27 and 28 are attached to the pivoted bar 26. As the pivoted bar 26 assumes the position indicated in dotted lines the upper actuating lever 28 moves the end chute gate 16 around into closed position, and the intermediate controlling lever 27 by reason of the construction of the bucket retainers 30 and 31 moves forward the coaling bucket 3 which is normally in engagement with the retainers, and releases the bucket therefrom when moved into the forward position indicated by dotted lines in Fig. 2 preparatory to 15 tilting the bucket downwardly, which is accomplished by means of the chain or cable 13.

A trigger 32^a is pivotally mounted on the post or column 9, which is adapted when in 20 closed position to engage a locking pin 33 on one of the bucket carriers 7 or otherwise. To the other end of the trigger 32^a is secured a cord and handle 34 for permitting the operator to release the loaded coal 25 bucket which will travel outwardly by its own weight, and when the coal is discharged from the bucket into the engine tender 35 the bucket automatically assumes its normal position adjacent the coal chute 11, the 30 movement back and forth of the bucket opening and closing the end chute gate 16, since the weights used are heavy enough to restore the empty bucket to normal position; so that all that is necessary for the 35 operator to do in coaling an engine tender is to actuate the trigger 32^a for releasing the bucket from normal position.

Although a preferred form of construction has been shown and described, it is not 40 intended to limit the invention strictly thereto since other equivalent devices may be employed for receiving, carrying, and discharging the coal.

I claim:

- 45 1. A coaling bucket, movable bucket carriers between which the bucket is mounted, a coal chute adjacent to the coaling bucket, an end chute gate, a movable bar positioned adjacent to the coaling bucket and chute, an intermediate controlling lever attached to said movable bar, a gate-actuating lever secured to said movable bar and end chute gate, a connecting member attached to the intermediate controlling lever, said intermediate controlling lever having retainers for engaging the coaling bucket when in normal position, and for releasing the bucket therefrom when advanced forward to discharging position, and means for re- 50 60 65 70 75 80 85 90 95 100 105 110 115 120
2. A coaling bucket, movable bucket carriers between which the bucket is mounted, a coal chute adjacent to the coaling bucket, an end chute gate, a movable bar positioned adjacent to the coaling bucket and chute, an intermediate controlling lever attached to said movable bar, a gate-actuating lever secured to said movable bar and end chute gate, a connecting member attached to the intermediate controlling lever, said intermediate controlling lever having retainers for engaging the coaling bucket when in normal position, and for releasing the bucket therefrom when advanced forward to discharging position, means for restoring the coaling bucket from discharging to normal position, and means for releasing the bucket carriers for discharging the bucket, substantially as described.
3. In a device of the class described, the combination of a bucket, a movable supporting member to which the bucket is pivotally attached, a coal chute adjacent the bucket, a chute gate, a movable forked member, a connection between said forked member and gate, the fingers of said forked member lying upon opposite sides of the rear wall of the bucket, substantially as described.
4. In a device of the class described, the combination of a bucket, a movable supporting member to which the bucket is pivotally attached, a coal chute adjacent the bucket, a chute gate, a movable forked member, a connection between said forked member and gate, the fingers of said forked member lying upon opposite sides of the rear wall of the bucket, the forward of said fingers being of less length than the rear whereby said bucket releases itself from engagement with said forked member when the bucket has been carried forward a predetermined distance and means for holding the chute gate in position after the release of the forked member from the bucket, substantially as described.
5. In a device of the class described, the combination of a bucket, a movable supporting member to which the bucket is attached, a coal chute adjacent the bucket, a chute gate, a movable forked member, a connection between said forked member and gate, and a connection between said forked member and bucket, substantially as described.
